CLAIM

The ornamental design for a drainage bag, as shown.

DESCRIPTION

FIG. 1 is a top plan view of a drainage bag showing my new design;

FIG. 2 is a bottom plan view thereof;

FIG. 3 is a side elevational view thereof, the opposite side elevational view being identical thereto; and,

FIG. 4 is a perspective view thereof.

FIG. 1**FIG. 2**FIG. 3

FIG. 4
